UNITED STATES PATENT OFFICE.

ISRAEL SILBER, OF CHICAGO, ILLINOIS.

GLADSTONE BAG.

Application filed March 24, 1921. Serial No. 455,115.

To all whom it may concern:

Be it known that I, ISRAEL SILBER, citizen of the United States, residing at Chicago, in the county of Cook and State of Illinois, have invented certain new and useful Improvements in a Gladstone Bag; and I do hereby declare the following to be a full, clear, and exact description of the invention, such as will enable others skilled 10 in the art to which it appertains to make and use the same.

My invention relates to means for stiffening and strengthening travelling bags and for improving the appearance of the same, 15 and more particularly for effecting these desirable improvements in connection with traveling bags of the types commonly known as "Gladstone" or "Railroad" bags.

In one of its prime objects, my invention 20 aims to provide simple, inexpensive and effective means for stiffening and strengthening such a bag so that it will more effectively resist both side pressures on the bag and downward pressures exerted upon 25 the top of the bag. Another prime object is that of providing reinforcements rigidly secured to certain of the supporting buttons or studs at the bottom of such a bag, so that the contents of a heavily loaded bag will be 30 supported primarily through these reinforcements and studs thereby avoiding undue strains on the leather and the lining of the bag. Still another object of my invention is that of providing simple means for 35 securing such reinforcements rigidly to a traveling bag, and of effecting this securing in such a manner that it will not interfere with the smooth interior of the bag and so that the presence of such reinforcements 40 will enhance the ornamental appearance of the bag. Still further and more detailed objects of my invention will appear from the following specification and from the accompanying drawings, in which—

Fig. 1 is a perspective view of a traveling bag equipped with the reinforcing and appearance-improving means of my invention.

Fig. 2 is an enlarged and horizontal section through a portion of one side of the 50 bag, taken along the correspondingly numbered line of Fig. 1.

Fig. 3 is an enlarged and fragmentary vertical section taken along the correspondingly numbered line of Fig. 1.

Fig. 4 is a bottom view of the bag.

In the embodiment of the drawings, the bag equipped with my invention is of the socalled "Gladstone" or "Railroad" type comprising two similar halves each fastened to a U-shaped frame, the said frames being 60 hinged to each other at their lower or free ends. Each half of the bag has its main casing composed of a cover 1 of leather stiffened with a thicker layer 2 of cardboard interposed between the leather 1 and a lining 3 65 of cloth or leather. Between the leather covering 1 and the cardboard in each half of the bag I insert a pair of stiffening and reinforcing members 4, each of which reinforcing members desirably consists of a strip of 70 metal bent flatwise into the form of a U and comprising a lower shank 4^a extending along the bottom of the bag, an upper portion 4^b extending along the top of the bag and a middle portion 4^c connecting the 75 parts 4^a and 4^b substantially as shown in Fig. 3. These reinforcements desirably are arranged in two pairs opposite each other on the two halves of the bag and with the central plane of the U of each member disposed transversely of the bag (or parallel to either end of the bag) and located at a distance from both ends of a bag. In practice, I desirably locate each of these reinforcements nearer to one end of the bag 80 than it is to the companion reinforcement in the same half of the bag. I also desirably make each such reinforcement of a stiff and substantially non-resilient metal, so that it will not readily be bent out of shape by 85 strains upon it. By so doing, I make these reinforcements effective in resisting both lateral strains upon the bag (such as a tendency to squeeze or compress the bag sideways) and downward pressure exerted upon 90 the top of the bag.

To prevent each such reinforcement from shifting in position, I secure the same immovably between the adjacent portion of the leather covering and of the cardboard lining, for which purpose I desirably employ rows 5 of stitching made through the leather and the cardboard adjacent to both edges of the metal reinforcement, and desirably have the stitches alongside each of the reinforcements extend through a strip of cloth or tape 6 disposed inside of the cardboard opposite the reinforcement. This tape prevents the stitching from tearing through the cardboard (which cardboard may then 105 110

be of fairly cheap grade) and hence insures a firm anchoring of the adjacent reinforcement, although the cloth strip or tape may be so thin as not to make the lining 3 5 bulge inward sufficiently to disclose the presence of such a strip or tape. While securing the parts to each other by this stitching, I desirably support the corresponding bag part in such a manner that the inner surface of the cardboard lining will 10 remain substantially flat or unindented by the adjacent metal reinforcing strip, thereby maintaining the desired smoothness of the cloth or leather lining 3 of the bag and 15 causing the thickness of the reinforcement to produce a corresponding bead effect along the exterior of the bag, substantially as shown in Figs. 1, 2 and 4 of the drawings. This bead effect adds considerably to the 20 handsome appearance of the finished bag, as it interrupts the otherwise monotonous surface of the sides and top of the bag, thereby enabling me to enhance the appearance of the bag by the same means which 25 afford the reinforcements.

As a further aid in strengthening the bag and particularly in distributing pressures exerted upon the top of the bag, I desirably support the bag when on the floor by buttons or studs including some which are directly anchored to the U-shaped reinforcements. In doing so, I preferably employ eight such studs or buttons instead of the usual six, namely four studs 7 disposed substantially under the corners of the bag and 30 four auxiliary studs 8, each of these auxiliary studs 8 being anchored to the bottom 4^A of one of the reinforcements. For this latter purpose, I desirably perforate the bottom portion 4^B of each reinforcement and employ studs 8, each of which forms the 35 head of a split or clincher rivet having a shank 9 which is driven both through the flap or extension portion of the bag side which laps under the bottom proper of the 40 bag and through this bottom. Thus, Fig. 3 shows the split shank 9 of the stud 8 as extending upwards successively through the bottom flap formed integral with the side 45 leather 1, the lower portion 4^A of one of the reinforcing strips, the bottom flap on the side cardboard reinforcement 2, the flap of the tip or webbing 6 on the same side of the bag, the bottom leather covering of the 50 bag, and the bottom cardboard lining 10. Then the inner cloth or leather lining 3 is disposed over this cardboard bottom piece 10 and over the spreadingly clinched tips 55 of the shank 9 of the stud, so as to cover 60 and conceal these portions.

In practice, I have found that I can produce an effective reinforcement for my purpose by employing a quite thin metal strip, such as a strip of iron 1/64th of an inch 65 thick, and that by suitably selecting the

grade of iron I can attain the desired rigidity and resistance against both downward and lateral strains on the bag. That is to say, if the bag as thus constructed is subjected to any lateral strains tending to 70 crush the same, the stiffness of the reinforcing strips will prevent the bag sides from being indented or flexed inwardly, thereby guarding the contents of the bag against injury and likewise preventing the 75 cardboard lining of the side from being unduly indented or even cracked. Likewise, if any heavy weight should be placed on the top of the bag, this weight will be supported primarily by the reinforcing strips, and 80 since these will transmit the thrust directly to the studs 8 at the bottom of the bag, the strain due to such a weight will not indent or otherwise injure the bag proper. I have 85 also found that by simply forming continuous rows of stitches as above described alongside the reinforcements, I practically incase each of these reinforcing strips in a tube in which the bent form of the reinforcement keeps the latter from moving. 90 I can therefore anchor these reinforcements in an effective position by very simple and cheap means, although I also desirably employ the studs 8 as above described in a manner which supplements this anchoring. As 95 a further means of augmenting the resistance of the bag against lateral compression, I may carry the shanks or horizontal portions of the U-shaped reinforcing strips up to the frame portions of the bag, as 100 shown for example at the top of Fig. 3, where the free end of the reinforcing strip portion 4^B abuts against the adjacent frame portion 12. However, while I have 105 illustrated and described my invention as applied to a particular shape of traveling bag and as including desirable details of arrangement and of construction, I do not wish to be limited to these, since it will be obvious that numerous changes might be made 110 without departing from the spirit of my invention or from the appended claims.

I claim as my invention:—

1. In a bag, a pair of hingedly connected U-frame members, a cover for each member including a lining, a leather facing, and a layer of cardboard interposed between the lining and leather facing, a bottom, metal reinforcing strips engaged with and interposed between the outer face of the cardboard and the inner face of the leather facing so as to bulge the latter outwardly to impart a bead-like appearance, said strips having inturned upper ends the end edges of which abut the adjacent parts of the 125 frame members and having inturned lower ends which engage beneath the bottom of the bag, tapes between the lining and cardboard registering with the metal strips, studs extending through the covers and the 130

5 inturned lower ends of the metal strips and through the bag bottom, and stitching extending through the lining tapes, cardboard and leather facing and along the sides of the metal strips to hold the latter against lateral movement.

2. In a bag, a pair of hingedly connected U-frame members, a cover for each member including a lining, a leather facing, and a 10 layer of cardboard interposed between the lining and leather facing, a bottom, metal reinforcing strips engaged with and interposed between the outer face of the cardboard and the inner face of the leather fac- 15 ing so as to bulge the latter outwardly to impart a bead-like appearance while permitting the cardboard and lining to remain flat, backing strips between the lining and cardboard registering with the metal strips, 20 means to secure the lower ends of the strips to the bag bottom, and stitching extending through the leather facing, cardboard, back-

ing and lining and adjacent to the sides of the metal strips to hold the latter in position.

3. In a bag, a pair of hingedly connected U-frame members, a cover for each member composed of layers of material, metal strips spaced from the bag ends and having in-turned ends interposed between the layers 30 of material, a bottom engaged on top of the lower inturned ends of the strips so as to be supported thereby, means to secure the bottom to said lower inturned strip ends, the upper ends of the strips abutting the 35 adjacent parts of the frame members, and rows of stitching extending along each side of each strip and extending through the layers of material to hold the strips against lateral movement and to impart a bead- 40 like effect to the cover.

Signed at Chicago, Illinois, March 17th, 1921.

ISRAEL SILBER.
